UNITED STATES PATENT OFFICE.

HARRY VISSERING AND LOUIS A. HOERR, OF ST. LOUIS, MISSOURI.

CAR-DOOR BRACKET.

SPECIFICATION forming part of Letters Patent No. 629,832, dated August 1, 1899.

Application filed February 9, 1899. Serial No. 705,114. (No model.)

To all whom it may concern:

Be it known that we, HARRY VISSERING and LOUIS A. HOERR, citizens of the United States, residing at the city of St. Louis, State of Missouri, have invented a certain new and useful Improvement in Car-Door Brackets, of which the following is a full, clear, and exact description, such as will enable others skilled in the art to which it appertains to make and use the same, reference being had to the accompanying drawings, forming part of this specification, in which—

Figure 1 is a side elevational view of our improved car-door bracket in position. Fig. 2 is a sectional view on line 2 2, showing our improved bracket in top plan; and Fig. 3 is a vertical sectional view on line 3 3, showing our bracket in edge elevation.

This invention relates to a new and useful improvement in car-door brackets designed particularly for use in connection with what are known as "flush" doors. Heretofore brackets have been made for sliding car-doors, in which the usual form is attached in position by lag-screws or bolts passing through the side sill, permitting an unauthorized person by the use of an ordinary wrench to remove said bolts, and in the absence of the bracket the car-door can be sprung outwardly, giving access to the car. Certain brackets are on the market, known as "burglar-proof" brackets, in which a hidden screw is provided or some means of attachment inaccessible from the exterior when the door is closed, whereby should the accessible bolts or lag-screws be removed the bracket cannot be displaced.

Due to the construction of cars and the manner of mounting the doors thereon burglar-proof brackets may be easily attached to the ordinary sliding door, known as the "outside" door—that is, a door which is not countersunk flush with the side wall of the car, but merely slid into a closed position on a straight track projecting outwardly beyond the side wall of the car a distance equal to or greater than the thickness of the door. A flush door, however, is countersunk, so as to be flush with the outside walls of the car, and fits into the doorway, its lower edge being above the side sill or sill-plate of the door, while in an outside door the lower edge of the

door projects from three to five inches below the door-opening.

As stated before, our improved bracket is designed particularly for use in connection with a flush door, and consists of a casting which is secured by suitable lag-screws or bolts passing through the side sill of the car-framing, said casting being extended upwardly along the side edge of the doorway, at which point a carriage-bolt is introduced, the nut on whose inner end is located inside of the car, so as to be inaccessible from the exterior when the door is closed. To prevent the bracket from being turned on said carriage-bolt as a pivot-point, dowels are also provided, which fit into recesses in the side wall of the car, and although the lower or main bolts be removed the bracket is held firmly in position by this single bolt and dowel.

In the drawings, A indicates the casting as an entirety, which is designed to be secured to the side wall of the car primarily by two or more bolts B, which, as shown in Figs. 2 and 3, pass through the side sills X of the car and the side walls Y thereof, their inner ends receiving suitable nuts b, but which, as is obvious, are accessible from underneath from the exterior by reaching under the car. From the body portion of this casting A is preferably offset slightly a wedge-shaped guiding projection C, closed at its inner end, which cooperates with the lower front edge of the door, first, to guide the same in its home position, and, second, to hold the same in said home position, as is well understood. This projection C is provided in its side with an opening c at the junction of the lower front corner of the door-opening for the purpose of permitting the escape or removal of foreign particles which might lodge behind the projection C and in front of the door proper and prevent the proper closing of the door. Projection C is strengthened by a rib D for obvious reasons.

E indicates a projection extending upwardly from the main casting A and above the projection C, which means also above the floor-line of the car. This projection E is to one side of the doorway and is provided with an opening to receive the square shank of a carriage-bolt, whose outer edge is preferably rounded, so as to prevent the application of

an ordinary wrench thereto, said carriage-bolt passing through the side wall of the car X and through the door-post Z, the inner end of said bolt within the car receiving a nut f.

5 G indicates dowel projections formed on the inner face of projection E and extending into the side wall of the car some distance, so as to prevent the turning of the casting in the absence of bolts B when the door is closed 10 and the nut on bolt F is inaccessible from the exterior.

In applying our improved casting suitable holes are bored for the bolts B B and F and shallow borings are made for the dowels G. 15 After the bolts are in position and the nuts added thereto the bracket is firmly secured to resist the rough treatment to which it is usually subjected. The object of having the bolts B in the position indicated is to sustain 20 heavy weights in the event that skids or platforms are placed by careless persons on the projection C of the bracket. When the door is closed, should an unauthorized person seek to gain access to the car the bolts B would of course be first removed and then attempt 25 would be made to rotate bolt F; but having a round head and a square shank passing through a square opening in the casting such rotation of this bolt would be impossible by 30 the application of a wrench exteriorly applied. Should a lever be introduced under the lower edge of the main casting for the purpose of springing the dowels out of their openings, the bolt F would act practically as 35 a fulcrum, and as one dowel moved outwardly the other one would be forced more firmly inwardly, thus absolutely preventing the rotation of the casting.

While we have shown and described our 40 improved bracket as being specially designed

for use in connection with a flush door, yet it is obvious that with slight changes to comply with given requirements the bracket could well be employed in connection with an outside door, subserving the purpose and function in that use the same as described with relation to its use in connection with a flush door. 45

Having thus described our invention, what we claim, and desire to secure by Letters Patent, is—

1. A car-door bracket substantially as herein described, comprising a casting, means for securing the same in proper position, and a guiding projection thereon closed at its inner 55 end and provided with an opening for the purposes set forth.

2. A car-door bracket substantially as herein described, comprising a body consisting of two portions adapted respectively to extend 60 above and below the floor of a car, a retaining projection for the door intermediate the two portions, retaining devices in the lower portion, and means in the upper portion for preventing outside detachment of the bracket 65 consisting of separated dowels embedded in the side of the car, a bolt held from rotation between the dowels and passing through the side of the car above the floor thereof, and locking means on the inside of the car for 70 preventing the withdrawal of said bolt.

In testimony whereof we hereunto affix our signatures, in the presence of two witnesses, this 30th day of January, 1899.

HARRY VISSERING.
LOUIS A. HOERR.
